JOHN R. McGIFFERT, OF DULUTH, MINNESOTA, ASSIGNOR TO CLYDE IRON WORKS, OF DULUTH, MINNESOTA, A CORPORATION OF MINNESOTA.

BOOM.

988,124.

Specification of Letters Patent. Patented Mar. 28, 1911.

Application filed December 7, 1910. Serial No. 596,003.

To all whom it may concern:

Be it known that I, JOHN R. McGIFFERT, a citizen of the United States, and a resident of Duluth, county of St. Louis, and State 5 of Minnesota, have invented a new and useful Improvement in Booms, of which the following is a specification, the principle of the invention being herein explained and the best mode in which I have contemplated applying that principle, so as to distinguish 10 it from other inventions.

In the construction of certain types of boom, as, for example, a boom comprising side members movably secured to each other 15 at their outer ends such as the boom employed in the machine for logging that forms the subject matter of my U. S. Patent No. 964,534, dated July 19, 1910, it has been found desirable to provide for a certain 20 amount of lateral sway of such members, and thus of the boom. In fact such provision may be found advantageous even in the case of a boom in which the side members are relatively fixedly secured together at 25 their outer ends, as in the more familiar construction. While a degree of flexibility in this particular may be secured by simply making the connection of the lower ends of the respective boom members with the support or socket on the machine frame or base 30 sufficiently loose to permit of a slight lateral swaying, as is described and claimed in the above named patent, I have devised a special construction of socket, or connection for 35 such lower ends of the boom members, which gives the desired flexibility without detracting in any way from the security of the structure and without any undue looseness of parts.

40 Said invention, then, consists of the means hereinafter fully described and particularly pointed out in the claims.

The annexed drawing and the following description set forth in detail certain mechanism embodying the invention, such disclosed means constituting, however, but one of various mechanical forms in which the principle of the invention may be used.

50 In said annexed drawing: Figure 1 is a broken plan view of a boom such as that first above described, with my present improvements incorporated therein; Fig. 2 is a side elevational view of the lower end of such boom; and Fig. 3 is a transverse sec-

tion; Fig. 4 longitudinal section, there- 55 through, taken on the lines 3—3 and 4—4, respectively, Fig. 1.

The boom proper, comprising in the present instance two side members 1, the outer ends of which are connected by a transversely disposed member 2 and pivot pins 12, so as to permit of relative movement between said ends, is not of itself of interest and hence need not be further described. It is to the spaced supports 3 on the base or 60 frame 4, of the machine, to which the lower end of said boom members are secured, that attention is desired. Each of these supports 3 comprises a plate formed with two similar, upwardly and forwardly projecting ears 5 65 pierced by transverse apertures 6 that are alined to receive a pin 7. Between said ears, and pivotally held in place by such pin, is a swivel bar 8, which it will thus be seen is capable of an oscillatory movement about the 70 axis of the pin. This swivel bar is in turn oscillatory secured in the lower end of the corresponding boom member 1, so as to permit of a twisting, or rotative, movement of the latter about the longitudinal axis of the 75 bar, which is obviously right-angularly related to the axis of the pin 7. Said bar is secured to the boom member by being fitted between two blocks 9, made in halves for this purpose, which are inserted between the 80 two channel bars that are utilized in the construction of the particular boom member here chosen for illustrative purposes. These blocks 9 are securely connected with such channels by means of bolts 10, the channels 85 themselves being held together by means of plates 11, riveted to their flanges. Other modes of rotatably securing the swivel members may of course be utilized where the 90 construction of the boom member varies 95 from the construction in question.

By means of the construction and arrangement of the parts just described, the side members of the boom are not only permitted an oscillatory movement in vertical planes 100 about the pins 7 in the supports 3 on the base, but said members are also permitted an independent movement about the central longitudinal axes defined by the axes of the respective swivel bars 8. The 105 boom structure as a whole is accordingly able to accommodate itself to the distorting effects of the strain of the skidding, or lift-

ing cables passing over its outer end, such as is bound to occur where the load is heavy, even if the guying cables are firmly secured. Indeed this twisting action has been found 5 sufficient to cause the side members of the boom to collapse, where provision is not made to accommodate the structure to this distortion; but by the present construction of swivel connection between the lower ends 10 of the boom and the base or support upon the latter, I have entirely overcome this difficulty.

Other modes of applying the principle of my invention may be employed instead of 15 the one explained, change being made as regards the mechanism herein disclosed, provided the means stated by any of the following claims or the equivalent of such stated means be employed.

20 I therefore particularly point out and distinctly claim as my invention:—

1. In mechanism of the character described, the combination with spaced supports; of a boom comprising side members 25 respectively secured to said supports at their lower ends so as to be pivotal about an axis substantially longitudinal of the corresponding member.

2. In mechanism of the character de- 30 scribed, the combination with spaced supports; of a boom comprising side members respectively secured to said supports at their lower ends so as to be pivotal about right- angularly related axes, substantially as de- 35 scribed.

3. In mechanism of the character de- 35 scribed, the combination with spaced supports; of a boom comprising side members respectively secured to said supports at their 40 lower ends so as to be pivotal about two

axes, one lying transversely of said supports, the other longitudinally of the member.

4. In mechanism of the character de- 45 scribed, the combination with spaced supports; of a boom comprising side members respectively secured to said supports at their lower ends so as to be pivotal about right- angularly related axes, the other ends of 50 said members being connected but movable relatively to each other.

5. In mechanism of the character de- 55 scribed, the combination with spaced supports consisting of plates formed with ears, and bars oscillatorily secured to said ears; of a boom comprising side members swiveled upon said bars at their lower ends.

6. In mechanism of the character de- 60 scribed, the combination with spaced supports consisting of plates formed with ears, and bars oscillatorily secured to said ears; of a boom comprising side members swiveled upon said bars at their lower ends, the other ends of said members being connected but movable relatively to each other.

7. In mechanism of the character de- 65 scribed, the combination with spaced supports consisting of plates each formed with two ears, and a swivel bar pinned at one end between said ears; of a boom comprising side members pivotally secured at their 70 lower ends to said bars, respectively, the outer ends of said members being connected but movable relatively to each other.

Signed by me this 30th day of November, 1910.

JOHN R. MCGIFFERT.
